United States Patent

Des. 236,920
Patented Sept. 23, 1975

236,920

CATHETER

David S. Sheridan, Argyle, N.Y., assignor to National
Catheter Corporation, Argyle, N.Y.

Continuation-in-part of abandoned design application Ser.
No. 455,927, Mar. 28, 1974. This application Aug. 19,
1974, Ser. No. 498,591

Term of patent 14 years

Int. Cl. D24—04

U.S. Cl. D83—12 A

FIG.1

FIG.2

FIG.3

FIG.4

FIG.5

FIG.6

FIG. 7

FIG. 8

FIG. 10

FIG. 9

FIG. 11

FIG. 1 is a side elevational view of the distal end of a catheter showing my new design;

FIG. 2 is a sectional view thereof taken along the line 2—2 in FIG. 1;

FIG. 3 is a sectional view taken along the line 3—3 in FIG. 1;

FIG. 4 is a front elevational view;

FIG. 5 is a side elevational view of the distal end of a catheter showing a modification of my new design;

FIG. 6 is a top plan view of the new design of FIG. 5;

FIG. 7 is a plan view of a catheter of my new design;

FIG. 8 is an enlarged perspective view of the distal end of the catheter as seen in FIG. 7;

FIG. 9 is a fragmentary top plan view of proximal end of my new catheter design;

FIG. 10 is a fragmentary bottom plan view of said proximal end; and

FIG. 11 is an end view of said proximal end.

This is a continuation-in-part of copending design application Ser. No. D. 455,927, filed Mar. 28, 1974, now abandoned.

I claim:

The ornamental design for a catheter, substantially as shown and described.
